UNITED STATES PATENT OFFICE.

GEORGE S. GRAVES AND WAYDE H. HOWARD, OF SEDALIA, MISSOURI.

OPERATING MECHANISM FOR GARAGE AND BARN DOORS.

Application filed October 6, 1922. Serial No. 592,902.

To all whom it may concern:

Be it known that we, GEORGE S. GRAVES and WAYDE H. HOWARD, citizens of the United States, residing at Sedalia, in the county of Pettis and State of Missouri, have invented new and useful Improvements in Operating Mechanism for Garage and Barn Doors, of which the following is a specification.

10 The invention relates to operating mechanism for garage or barn doors.

The object of the present invention is to provide a simple, practical and efficient operating mechanism for garage and barn doors and the like of strong and durable construction adapted to form an efficient lock for such a door and capable of being readily operated by a person within an automobile or other conveyance without leaving the same.

20 A further object of the invention is to provide door operating mechanism of this character equipped with an interiorly arranged latch and capable of being operated exteriorly of the door at a distance from the same to unlock the door and move the same to an open position or to close the door and lock the same.

With these and other objects in view the invention consists in the construction and 30 novel combination and arrangement of parts hereinafter fully described, illustrated in the accompanying drawing and pointed out in the claims hereto appended, it being understood that various changes in the form, 35 proportion and minor details of construction, within the scope of the claims, may be resorted to without departing from the spirit or sacrificing any of the advantages of the invention.

40 In the drawing, in which like characters of reference designate corresponding parts in the several views:—

Figure 1 is a perspective view of a portion of a garage equipped with door operating mechanism constructed in accordance with this invention, the door being closed.

45 Figure 7 is an enlarged detail view illustrating the arrangement of the latch operating mechanism when the same is unlocked.

In the accompanying drawing, in which is illustrated the preferred embodiment of the invention, the operating mechanism which is shown applied to a garage, comprising in 50 its construction spaced sprocket wheels 1 and 2 mounted on shafts 3 and 4 and receiv-

ing an endless sprocket chain 5 and located above the top of the door 6 of the garage and extending substantially horizontally across the garage above the door opening 7. The door 6 is composed of sections 8 connected together by upper and lower hinges 9 and suspended by hangers 10 from a track 11. The track 11, which is secured by suitable brackets 12 to the garage door interiorly thereof, extends across the garage above the door opening and is provided at one side of the garage with a rearwardly extending portion 13. The rearwardly extending portion is connected with the front portion by a curved intermediate portion 14 and the track permits the sections of the door to slide along it from a closed position at the front of the garage to an open position at one side of the garage, as will be readily understood.

The lower stretch or portion of the sprocket chain is connected by a bolt 15 with the upper end of a latch operating lever 16 pivoted intermediate of its ends by a bolt 17 or other suitable fastening device to the front section of the door 6 at the upper portion thereof and arranged in substantially a perpendicular position when the garage door is closed. The upper portion of the latch operating lever is adapted by the movement of the sprocket chain to be carried into abutting relation with the hanger of the front section of the door and the said latch operating lever, which has a limited pivotal movement independently of the door for operating a latch 18, has its lower portion arranged within an approximately horizontal guide 19 and is connected at its lower end with the latch 18 by a short chain 20. The latch 18 preferably consists of a bar or member pivoted at its inner or rear end in a suitable bracket 21 by a bolt 22 and it is connected intermediate of its end to the lower end of the short chain 20 which extends upwardly from the latch through a guide 23 which is located directly beneath the lower end of the latch operating lever when the door is closed. The guide 23, which can be of any desired construction, may conveniently consist of a screw eye and when the lower end of the latch operating lever is swung from a position directly above the guide 23 the chain will be drawn through the said guide and will lift the latch to the position illustrated in Figure 2 of the drawing and disengage the front end 24 of the latch from a keeper

25. The front end of the latch is preferably extended downwardly, as shown, to form an engaging portion which is adapted to drop into the keeper 25. The keeper 25 is approximately L-shaped and it has a projecting horizontal portion having an opening arranged to receive the terminal engaging portion of the latch and a vertical guide 26 is preferably provided for the latter. The 10 guide 26 is secured to the front section of the door 6 and is arranged adjacent the front end of the latch.

The shaft 3 of the sprocket wheel 1 is preferably in the form of a stub shaft and 15 the shaft 3 of the sprocket wheel 2 preferably consists of a rod arranged in a pipe 3^a of steel or other suitable material extending in advance of the garage a distance of 10 or 12 feet to enable a detachable operating 20 crank or key 27 to be readily grasped and operated by a person within a car without leaving the same. In practice the crank or key which fits in the outer portion of the tubular shaft or pipe, will be of different 25 designs or forms for different doors so that each crank will fit only its particular shaft 3. Either the shaft 3 or the crank 27 may be provided with a socket so that one part may be fitted on or into the other.

30. The garage is designed to be provided at the bottom of the door opening with suitable guiding means for preventing lateral movement of the bottom portion of the garage door. While the operating device is 35 shown applied to a garage door it is readily apparent that it may be advantageously employed in connection with barn doors and various other kinds of doors where an operating and locking mechanism of this character is desired. When the door is closed and the operating shaft is rotated the first movement of the gearing is to swing the latch operating lever 16 and lift the latch and the continued movement of the gearing 40 will open the door. The reverse movement of the gearing will close the door and lock the same. The horizontal keeper 19 and the hanger of the front section of the door will limit the movement of the latch operating 45 lever and relieve the chain 20 and latch of undue strain.

What is claimed is:

1. The combination with a building having a sliding door, a curved track and 55 hanger suspending the door from the building, spaced sprocket wheels located within the building above the door opening and track, an endless sprocket chain arranged on the sprocket wheels, a relatively long latch 60 operating lever pivoted intermediate its ends at the front edge of the door and extending above the door opening and connected at its upper end to the sprocket chain and arranged adjacent to one of the hangers to be carried 65 into and out of abutting relation with the

same by the sprocket chain, a gravity operated latch mounted on the inside of the door, a short flexible element suspended from the lower end of said lever and connected to said latch intermediate the ends of the latter, the pivotal movement of the lever raising the latch to allow the door to open, a keeper on the door frame, the reverse pivotal movement of the lever when closing the door maintaining the latch in elevated 75 position until the same is above the keeper. 70

2. The combination of a sliding door, of spaced sprocket gears located above the door, an endless sprocket chain arranged on said gears, a latch operating lever pivoted intermediate its ends to the upper edge of the door and connected at its upper end to the lower run of the sprocket chain, a latch pivotally mounted on the inside of the door and located below the latch operating lever, a 80 guide mounted on the door adjacent the lower end of the latch operating lever, a short flexible connection extending through the said guide and attached to the latch and to the lower end of the latch operating lever, whereby upon operation of the chain, the latch operating lever is moved upon its pivot and the latch raised and lowered according to the direction of movement of the 85 endless sprocket chain, a relatively long shaft 90 extending outwardly from one of said gears, and means whereby to rotate said shaft from an automobile or other vehicle to actuate the sprocket chain to open and close the door 95 without the operator leaving the vehicle. 100

3. The combination of a building provided with a sliding door, of spaced interiorly arranged sprocket gears located above the door, an interiorly arranged latch, a sprocket chain arranged within the building on the sprocket gears above the door, means for connecting the latch with the sprocket chain for operating the latch when the chain is moved, a relatively long shaft connected with one of the sprocket wheels and extending to 105 a point exteriorly of the door, and a removable crank key adapted for interlocking connection with said relatively long shaft for rotating the latter to actuate said endless chain and thereby open and close the door. 110

4. The combination with a sliding door, of spaced interiorly arranged sprocket gears located above the door, an interiorly arranged latch, a sprocket chain arranged on the sprocket gears, means for connecting the latch with the sprocket chain for operating the latch when the chain is moved, a shaft connected with one of the sprocket wheels and extending to a point exteriorly of the door and provided at its outer end with an 120 engaging portion, and a removable crank key engaging the outer end of the shaft, one of the parts having a socket receiving the other part and interlocking the key with the shaft for rotating the latter. 125

5. The combination with a sliding door, crank key fitting in the outer end of the tube
interiorly arranged gearing connected with and engaging the rod for operating the gear-
ing to open and close the door. 10
having a rotary element, a shaft connected
5 with the rotary element and extending ex-
teriorly of the door, a tube receiving and
concealing the said rod and a removable
- In testimony whereof we have hereunto
set our hands.

GEORGE S. GRAVES.
WAYDE H. HOWARD.
